UNITED STATES PATENT OFFICE.

SAMUEL K. WELLMAN, OF CLEVELAND HEIGHTS, AND ALLEN A. GOULD, OF CLEVELAND, OHIO.

LUBRICANT CONTAINER FOR GREASE GUNS.

Application filed December 16, 1925. Serial No. 76,189.

The invention relates to an improved form of lubricant container preferably adapted to be inserted like a cartridge in a grease gun and has to do particularly with the type of 5 lubricant container or cartridge disclosed in our pending application Serial No. 10,344, filed February 19, 1925, and which is adapted for use in connection with grease guns of the type having a discharge nozzle with 10 pump mechanism adapted to suck lubricant from the chamber of the gun and force it out of the nozzle, although the invention in some of its aspects is applicable to containers other than those of the cartridge type.

15 The chief objects of our invention are comprehended in the provision of a cartridge-like container of the character referred to which is adapted to serve satisfactorily as a container in which the grease can be packed 20 and marketed, which readily can be inserted in a suitable grease gun of the character disclosed in our pending application above referred to, which is adapted to cooperate effectively with the nozzle mechanism of such 25 gun to discharge the grease therefrom, and which finally, is susceptible of being manufactured at very low cost.

30 A further object of the invention is the provision of a tubular lubricant container having an improved piston-like end wall structure adapted to move within the tubular side wall of the container under atmospheric pressure as the grease is drawn from the container.

35 Other objects incidental or ancillary to the foregoing will appear from the following description in which we set forth in connection with the accompanying drawing the preferred forms or embodiments of our invention.

40 In the accompanying drawing, Fig. 1 is a side elevation of a cartridge constituting one embodiment of our invention, some of the cartridge being broken away to show parts 45 of the structure in longitudinal section.

Fig. 2 is a longitudinal axial section through a cartridge presenting a modified form of end wall or piston.

50 Figs. 3, 4, 5 and 6 show in axial section, four other forms of piston construction, the piston in each instance being adapted for

use in cartridges such as shown in Figs. 1 and 2 in lieu of the pistons thereof.

Fig. 7 is a longitudinal sectional view of 55 a grease gun with the cartridge shown in Fig. 1 operatively mounted therein.

A grease gun of the general type with which our improved containers are designed to be used will first be briefly described in order that the characteristic features of the 60 container may be clearly understood. 1 designates the chambered body or barrel of the grease gun. The body is ordinarily tapered at 1° toward its discharge end and is 65 fitted with a nozzle or head 2. The nozzle 2 is fitted with a pump mechanism adapted to suck lubricant from the chambered body of the gun and force it from the end of the nozzle in a well-known manner. In so far as the present invention is concerned this 70 pump mechanism may be of any suitable construction. The specific form of pump mechanism shown is that of a commercially known grease gun and it will suffice to point out that it comprises a plunger 3 having a 75 passage therethrough controlled by a spring pressed ball valve 4. 5 is a spring pressed check valve which controls the passage through a fixed abutment plate 6. A coil spring 7 is interposed between the abutment plate 6 and the plunger 3. The outer end of the nozzle 2 is designed to engage a fitting of the bearing to be lubricated, such as shown in a. This fitting a is formed with diametrically opposite lugs or pins a', a', 80 and the nozzle 2 is formed with opposite spiral slots 2a, 2a to engage the pins a'. In the use of the gun the nozzle 2 is engaged with the fitting a with the pins a' in the slots 2a. Then the gun is twisted about its 85 longitudinal axis and this causes the end of the fitting a to press the plunger 3 toward the check valve 5 thus forcing lubricant past the ball valve 4 into the nozzle of the gun. On reversing the twisting movement of the 90 gun, the spring 7 returns the plunger 3 to its normal position thereby exerting a suction on the lubricant tending to draw it from the body of the gun past the check valve 5.

95 The outer open end of the gun barrel is normally closed by a cap 8 which is detachably secured to the barrel of the gun by bayonet 100

slot connections comprising slots 8^a formed in the flange of the cap and pins or lugs 9 carried by the gun barrel.

As heretofore constructed this pump type of grease gun has had the lubricant introduced directly into the body or barrel of the gun and has been fitted with a piston-like follower so that when the lubricant at the inner or nozzle end of the gun is subjected to suction, atmospheric pressure on the follower forces the lubricant forward toward the nozzle end of the gun. But by employing our improved grease cartridges we do away entirely with the follower engaging the inner walls of the barrel of the grease gun, and instead of introducing the lubricant into direct engagement with the body of the grease gun we introduce the lubricant-filled cartridge bodily into the barrel of the grease gun.

Our improved cartridge, in the form illustrated in Fig. 1 comprises a tubular side wall 10, said wall preferably consisting of an inner tube 10^a and a somewhat shorter outer tube 10^b. The inner or discharge end of the container is formed by a cap or closure 11 which fits the projecting end of the inner tube 10^a as shown. The cap 11 is preferably secured to the side wall by a paper seal (not shown) over its joint with the side wall, which seal can readily be broken or cut to permit removal of the cap before the cartridge is inserted in the gun. The cap 11 thus constitutes an end wall for the cartridge which readily can be opened to permit discharge of the lubricant. The cartridge is provided at its other end with an end wall 12 which serves also as a piston or follower adapted to slide within the tubular side wall of the cartridge. The piston 12 comprises a transverse wall member 12^a which is formed at its periphery with an outwardly turned flexible flange 12^b adapted to closely fit and conform to the inner side wall 45 of the cartridge. Within the flange of the member 12^a and rigidly secured thereto is a tubular member 12^c which projects outwardly from the member 12^a and has at its outer end an outwardly turned flange 12^d to lightly, slidably engage the inner wall of the cartridge. The flange 12^d being substantially spaced longitudinally of the cartridge from the flange 12^b, there is provided for the piston-like end wall a relatively wide engagement with the side wall of the cartridge so that the piston is maintained in suitable axial alignment with said side wall and cramping or binding of the piston and admission of air past it is prevented. In addition to the piston or follower 12, the cartridge has at its outer end a closure or cap 13 which fits the projecting end of the side wall tube 10^a. This cap serves chiefly as a means for preventing accidental displacement or escape of the piston 12 from the

cartridge. The cap 13 has a central aperture 13^a through which one's finger or any suitable tool can be inserted when desired to press the piston toward the discharge end of the cartridge, and also through which the atmosphere can reach the follower 12, both functions being hereinafter described.

While our invention, in certain of its aspects at least, is not limited to the use of any particular material for the walls of the cartridge or container, as any oil-proof material adapted to give the cartridge a suitable amount of rigidity can be employed, we prefer in the interest of low cost and light weight to use an oil-proofed paper or fibrous material of suitable thickness. The oil proofing of such fibrous material is preferably effected by a treatment with silicate of soda or with lacquers having a cellulose base or with other suitable material. We do not limit our invention to the use of any particular material for the treatment since any suitable oil-proofing treatment can be used. The cartridge can be formed of sheet metal of suitable thickness but, as above indicated, lower cost is obtained by the use of the suitably treated fibrous material. The tubular side walls of such fibrous material are readily formed in the well-known manner as are also the caps or closures 11 and 13. The piston similarly is readily produced. That is to say the member 12^a is readily formed by pressing a suitable disc of paper or fibrous material in suitable dies and the member 12^c is formed from a section of paper tube or the like by simply pressing one end outward in suitable dies to form its flanges 12^d. The member 12^c is then readily secured to the member 12^a as by means of the silicate of soda or the like which is employed to oil proof the parts.

A container such as has been described is readily charged with lubricant at the factory. It is then closed by applying and sealing the cap 11. The cartridge or package thus formed is readily and conveniently handled as an article of commerce and when the lubricant is to be used it is only necessary for the user to remove the cap 11 and insert the cartridge bodily into the barrel of the grease gun, first removing, of course, the cap 8. The length of the cartridge is made such in relation to the barrel of the gun that when the cartridge is inserted in the gun and the cap 8 is applied said cap forces the container inward and effects a substantially air tight annular seal between the inner end of the side wall of the cartridge and the adjacent tapering wall 1^a of the body of the gun. In fact it is preferable to make the dimensions of the cartridge such that when the cap 8 is secured by means of its bayonet connection the inner end of the cartridge has its edge forced slightly inward by the pressure as indicated in Fig. 7. This has

the advantage of insuring a tight seal and in addition the inturned edge of the cartridge side wall serves to engage the piston or follower 12 of the emptied cartridge and insure the removal of the follower with the side wall as the emptied cartridge is withdrawn from the gun.

With the grease gun loaded by the insertion of a cartridge in the manner described it is only necessary for the operator to apply it to a bearing fitting such as that indicated at α in Fig. 7 and actuate the pump mechanism by a back and forth twisting movement, in order to create a suction which, by reason of the atmospheric pressure back of the piston or follower 12, results in the latter moving forward in the cartridge so that the lubricant is advanced to the pump mechanism. As use of the gun is continued the piston or follower 12 continues to advance toward the discharge end of the gun and finally completely empties the cartridge, the piston having a substantially flat front face to insure such complete emptying.

In the operation of the gun as described, the flange 12^b of the piston or follower, by reason of its flexible nature, conforms closely to the inner wall of the cartridge and with the atmospheric pressure back of it effects a substantially air-tight fit with the said side wall, the lubricant assisting to effect the seal. While the piston flange 12^b has the necessary flexibility as above described, it serves in conjunction with the guide flange 12^a to maintain the piston in proper axial alignment as above described so that it cannot be turned in the barrel of the cartridge by the atmospheric pressure as suction is created on the front side of the piston.

When a cartridge has been emptied of lubricant by use of the gun as above described, the gun is very easily re-loaded by simply detaching the cap 8, removing the empty cartridge and inserting a full one in the manner previously described, this operation being effected without the necessity of directly handling or touching the grease so that an operation which is ordinarily a very mussy one is made very simple and cleanly.

After the gun has been placed in use the forward neck portion of the gun between the discharge end of the cartridge and the stationary check valve of the pump mechanism becomes filled with lubricant so that when a full cartridge of lubricant is inserted in the gun the latter is in condition to at once discharge lubricant from the nozzle without any preliminary actuation of the pump mechanism to effect "priming". However, in putting the grease gun to use in the first instance it is desirable to fill the said forward neck portion of the gun with lubricant without relying upon the pump mechanism to effect the priming. This the user can readily do when the initial cartridge is in-

serted into the gun, by inserting his finger or a suitable tool through the aperture in the rear cap 13 of the cartridge and pressing the follower 12 forward to eject sufficient grease to fill the said neck portion of the gun. 70

The modified form of cartridge illustrated in Fig. 2 differs from that shown in Figs. 1 and 7 only in the construction of the piston end wall or follower. It will be sufficient therefore to describe this latter part 75 only of the construction. The piston or follower in this instance comprises a forward transverse wall member 14 formed with a flexible rearwardly turned flange 14^a which closely engages and conforms to the inner 80 wall of the cartridge so as to form a substantially air-tight sliding seal therewith, said member thus being substantially the same as the member 12^a of the piston illustrated in Figs. 1 and 7. Secured to the 85 member 12 is a cupped member 15 which has its transverse wall 15^a secured to the transverse wall of the member 14 while its rear or outward edge lightly engages the inner wall of the cartridge and serves to 90 hold the piston in axial alignment.

The piston illustrated in Fig. 2 is preferably made of suitably treated paper or other fibrous material. As in the case of the piston of the first described cartridge the guide 95 member 15 should be made heavy enough to properly perform its function of guiding.

In Fig. 3 of the drawing is illustrated still another form of the piston or follower embodying our ideas. In this construction the piston comprises a plain front disc member 16, the outer edges of which are adapted to lightly engage the inner wall of the cartridge, and a cupped member 17 secured thereto and having its rear flanged edge 17^a 100 sufficiently flexible to closely engage and conform to the inner wall of the cartridge and effect a substantially air-tight sliding seal therewith. This form of construction also is preferably made of suitably treated paper 105 or fiber.

In Fig. 4 we show still another form of piston which comprises a plain front disc 18 preferably of metal and a cupped member 19 preferably of paper, fiber or the like, the member 19 being secured to the member 18 by disc 20 and rivet 21. In this construction the outer edge of the disc 18 lightly engages the inner wall of the cartridge in which it is used while the rear flexible edge 120 of the member 19 closely engages and conforms to the inner wall of said cartridge to effect a substantially air-tight seal.

In Fig. 5 we show a piston or follower 125 which consists of a metallic cupped member 22 the side wall of which is formed near its front side with a channel to receive a flexible packing ring 23 of felt, leather or the like. This flexible packing ring 23 closely engages and conforms to the inner 130

wall of the cartridge in which the follower is used and when saturated with grease forms a substantially air-tight seal therewith. At the same time the rear edge 22^a of the flanged member 22 is adapted to lightly engage the inner wall of the cartridge.

Finally, in Fig. 6 is shown a follower which consists simply of a deeply cupped member 24 the side or flange wall 24^a of which flares slightly toward the outer (right) side of the follower so that the free flexible edge of said side wall is adapted to closely engage and conform to the surrounding side wall of the container while the transverse wall of the follower, at its periphery where it joins the side wall, lightly engages the side wall of the container. Thus the free edge of the follower forms a substantially air-tight sliding seal with the side wall of the container while the contact of the front or inner edge of the follower at points widely separated from the rear, seal edge, affords an adequate guiding action for the follower. This form of follower can be made either of oil-proofed fibrous material or of metal of suitable character.

It will be understood that the pistons or followers illustrated in Figs. 3, 4, 5 and 6, as well as that illustrated in Fig. 2, are designed to perform the same function as the follower 12 of Fig. 1 and are interchangeable therewith. Also, it will be noted that in each form of piston or follower disclosed there is a flexible peripheral part which closely engages and conforms to the inner wall of the cartridge to effect a substantially air-tight seal, and a circumferentially extending guide portion which is adapted to lightly engage the side wall of the cartridge at a number of points distributed around the circumference thereof and substantially spaced lengthwise of the cartridge from the annular seal portion, so that in each form of piston construction the piston is effectively held in axial alignment in the side wall of the cartridge. While in each form of construction illustrated the guide member of the piston forms a substantially continuous circumferential engagement with the side wall of the cartridge, it is obvious that such engagement need not be continuous, provided there are points of engagement suitably distributed around the circumference of the piston.

From the foregoing it will be seen that our improved cartridge not only constitutes a satisfactory container for the marketing of grease but is capable of highly convenient use and effective functioning in grease guns of the character described and at the same time is adapted to be produced at a very low cost.

While we have illustrated several preferred or suitable forms of construction to

embody our improvements it will be understood that there can be still other variations without departing from the invention as defined in the appended claims.

What we claim is:

1. A container for lubricant adapted to cooperate with a discharge nozzle having pump mechanism adapted to suck lubricant from the container and force it out of the nozzle, said container comprising in combination a tubular side wall; a substantially flat end wall adapted to be opened to permit discharge of lubricant; and a second end wall fitting within the side wall and adapted to be moved therethrough like a piston by air pressure to discharge lubricant from the container, said piston-like end wall having a substantially flat front face, a flexible rearwardly turned annular seal portion to engage the side wall and form a substantially air-tight sliding seal therewith and a guide portion to engage the side wall at points distributed around the circumference thereof and substantially spaced lengthwise of the container from the annular seal portion. 90

2. A cartridge-like container for lubricant adapted to be inserted into the chambered body of a lubricant gun having a discharge nozzle with pump mechanism adapted to suck lubricant from the chamber of the gun and force it out of the nozzle, said container comprising in combination a tubular side wall; a substantially flat end wall adapted to be opened to permit discharge of lubricant; and a second end wall fitting within the side wall and adapted to be moved therethrough like a piston by air pressure to discharge lubricant from the container, said piston-like end wall having a substantially flat front face, a flexible rearwardly turned annular seal portion to engage the side wall and form a substantially air-tight sliding seal therewith and a guide portion to engage the side wall at points distributed around the circumference thereof and substantially spaced lengthwise of the container from the annular seal portion. 100

3. A container for lubricant adapted to cooperate with a discharge nozzle having pump mechanism adapted to suck lubricant from the container and force it out of the nozzle, said container comprising in combination a tubular side wall; an end wall adapted to be opened to permit discharge of lubricant; and a second end wall fitting within the side wall and adapted to be moved therethrough like a piston by air pressure to discharge lubricant from the container, said piston-like end wall having a transverse portion formed with a flexible rearwardly turned annular flange to engage the side wall and form a substantially air-tight sliding seal therewith and a guide portion to engage the side wall at points distributed around the circumference thereof and sub- 130

stantially spaced lengthwise of the container from the annular seal portion.

4. A cartridge-like container for lubricant adapted to be inserted into the chambered body of a lubricant gun having a discharge nozzle with pump mechanism adapted to suck lubricant from the chamber of the gun and force it out of the nozzle, said container comprising in combination a tubular side wall; an end wall adapted to be opened to permit discharge of lubricant; and a second end wall fitting within the side wall and adapted to be moved therethrough like a piston by air pressure to discharge lubricant from the container, said piston-like end wall having a transverse portion formed with a flexible rearwardly turned annular flange to engage the side wall and form a substantially air-tight sliding seal therewith and a guide portion to engage the side wall at points distributed around the circumference thereof and substantially spaced lengthwise of the container from the annular seal portion.
5. A container for lubricant adapted to cooperate with a discharge nozzle having pump mechanism adapted to suck lubricant from the container and force it out of the nozzle, said container comprising in combination a tubular side wall; an end wall adapted to be opened to permit discharge of lubricant; and a second end wall fitting within the side wall and adapted to be moved therethrough like a piston by air pressure to discharge lubricant from the container, said piston-like end wall having a transverse portion formed with a flexible rearwardly turned annular flange to engage the side wall and form a substantially air-tight sliding seal therewith and a guide portion to engage the side wall at points distributed around the circumference thereof and substantially spaced lengthwise of the container from the annular seal portion.
6. A cartridge-like container for lubricant adapted to be inserted into the chambered body of a lubricant gun having a discharge nozzle with pump mechanism adapted to suck lubricant from the chamber of the gun and force it out of the nozzle, said container comprising in combination a tubular side wall; an end wall adapted to be opened to permit discharge of lubricant; and a second end wall fitting within the side wall and adapted to be moved therethrough like a piston by air pressure to discharge lubricant from the container, said piston-like end wall having a transverse portion formed with a flexible rearwardly turned annular flange to engage the side wall and form a substantially air-tight sliding seal therewith and a guide portion to engage the side wall at points distributed around the circumference thereof and substantially spaced lengthwise of the container from the annular seal portion.
7. A container for lubricant adapted to cooperate with a discharge nozzle having pump mechanism adapted to suck lubricant from the container and force it out of the nozzle, said container comprising in combination a tubular side wall; an end wall adapted to be opened to permit discharge of lubricant; and a second end wall fitting within the side wall and adapted to be moved therethrough like a piston by air pressure to discharge lubricant from the container, said piston-like end wall having a transverse portion formed with a flexible rearwardly turned annular flange to engage the side wall and form a substantially air-tight sliding seal therewith and a guide portion to engage the side wall at points distributed around the circumference thereof and substantially spaced lengthwise of the container from the annular seal portion; and a cap on the end of the container adjacent the piston-like end wall, said cap being adapted to prevent rearward movement of the piston-like end wall from the bore of the side wall and having an aperture through which the said piston-like end wall can be engaged to force it toward the opposite end of the container.

In testimony whereof, we hereunto affix our signatures.

SAMUEL K. WELLMAN.
ALLEN A. GOULD.
